UNITED STATES PATENT OFFICE

JOHN G. McCLEAN, OF CHICAGO, ILLINOIS, ASSIGNOR TO THE GRANT MANUFACTURING AND MACHINE COMPANY, OF BRIDGEPORT, CONNECTICUT, A CORPORATION OF CONNECTICUT

RIVETING MACHINE

Application filed September 24, 1929. Serial No. 394,758.

This invention relates to new and useful improvements in riveting machines such as are used for forming heads on rivets and other metal articles.

5 The invention more particularly applies to medium sized riveting machines of the type wherein relatively light but very rapid blows are struck by the riveting head of the hammer and to which is also imparted rotary movement.

10 A feature of the invention is to provide an improved form of helve having novel driving connections and improved flexible means for supporting the hammer from the helve and further includes inclosed rotatable driving connection of rotary drive and hammer spindle.

15 A further object of the invention is to provide an adjustable table beneath the hammer for supporting the work to be riveted.

20 With these and other objects in view, the invention resides and consists in the construction and novel combination and arrangement of parts hereinafter more fully described, 25 illustrated in the accompanying drawings, and pointed out in the claims hereto appended, it being understood that various changes in the form, proportion, size and minor details of construction within the scope of the 30 claims may be resorted to without departure from the spirit, or sacrificing any of the advantages of the invention.

Similar characters of reference denote like or corresponding parts throughout the several figures, of the accompanying drawings forming a part of this specification and upon which

35 Fig. 1 shows a side elevation of my improved riveting hammer;

40 Fig. 2 is a top plan view on a slightly enlarged scale of the machine shown in Fig. 1, the motor for driving the machine being omitted;

45 Fig. 3 is an enlarged vertical section taken on line 3-3 of Fig. 1 looking in the direction of the arrow;

50 Fig. 4 is a central vertical section taken on line 4-4 of Fig. 2 better to illustrate the hammer and its rotating and reciprocating driving connections; and

Fig. 5 shows a detached perspective view of the pivotal block 65 used in the hinged connection of helve with driving eccentric.

55 Referring in detail to the characters of reference marked upon the drawings, 6 indicates the base of a pedestal 7 which supports the several parts of the machine. This pedestal includes a forwardly projected arm 8 which carries the reciprocatory hammer again to be referred to and also includes a 60 pair of upwardly extended bearings 9-9 in which the helve is pivotally supported. A hollow support 10 is secured to the base, and in it is mounted a post 11 whose lower threaded end portion 12 is provided with attached 65 threaded adjusting nuts 13 and 14, the latter being positioned upon the top of the support 10 and the two serving to adjustably retain the post upon and within the support. The 70 upward end of this post is suitably connected as at 15 with a table 16 positioned beneath the hammer head in a way to support work thereon to be riveted. This table is provided with suitable ways 17 to engage vertical guides 18 formed upon the face of the pedestal and whereby the table is free to be raised and lowered through the action of the post and its adjusting nuts 13 and 14. The face of the column is further provided with aligned vertical slots in which is mounted 75 bolts 19 that are carried in suitable holes of the flanges of the table and are provided with nuts 20 whereby the bolts and nuts may be tightened to clamp the table to the column and firmly support the same below and with respect to the hammer which strikes down 80 toward the face of the table.

85 21 represents an electric motor which is secured to the back of the pedestal and is operatively connected by means of a belt 22 with a driving pulley 23 normally loose upon a shaft 24 journaled in aligned bearings 25-25 of the hubbed portions 26 of the pedestal. The 90 driving connection of the shaft 24 with the pulley 23 is made through a clutch mechanism, the outer member 27 of which is pinned to the outer end portion of the shaft 24 and has an annular face which bears upon an annular surface on one side of the pulley 23. A 95 somewhat similar though movable clutch 100

member 28 is mounted upon the inner squared portion 29 of the shaft 24 to turn therewith and is also provided with an annular friction surface to bear upon the inner side of the driving pulley in opposite relation to that of the previously mentioned clutch member 27 so that as the clutch member 28 is moved in and out it will engage the pulley 23 in a way to clamp the latter between the two said clutch members and insure the turning of the shaft with the pulley when thus engaged. This clutch is made operable through a rotatable adjustable ring 30 having an internal thread that engages a corresponding thread 31 in the periphery of the extended end portion of the bearing 25 which is secured within the hub of the pedestal 7. The outer annular face of this adjustable ring member 30 bears against the side face of one member of a roller bearing 32 positioned in an annular recess of the friction member 28 so that the latter is free to run with respect to and independent of the said adjusting ring 30. This adjusting ring, see Fig. 1, is provided with a radially disposed arm 33 to which a rod 34 is adjustably connected. The lower end of this rod is attached to a foot pedal lever 35 that is pivoted as at 36 within the pedestal of the machine and is provided with a spring 37 which normally tends to hold the foot pedal and its connecting rod in a raised position and the adjusting ring and clutch member in a disengaged position.

In this connection brake means are also provided for stopping the clutch member 28, shaft 24 and hammer, which includes a brake shoe 38, one end of which is pivoted at 39 to the pedestal and the other end in movable engagement as at 40 with rod 34. A friction piece 41 is attached to the face of the brake shoe for engagement with the periphery of the clutch member 28 mounted on shaft 24.

It will thus be seen that the shaft 24 is connected to be driven only when the clutch is engaged and is automatically stopped by release of clutch and application of brake when the foot pedal 35 is released.

Upon the opposite end portion of the driven shaft 24 is mounted a belt wheel 42 which carries a belt 43 connected to drive a small pulley 44 upon a shaft 45 journaled crosswise of and in the arm 8. This cross shaft carries a worm 46 which meshes with and drives a worm gear 47 splined to the reciprocating and rotatable hammer spindle 48 journaled in suitable bearings 49 positioned in the before mentioned arm 8 in a way to rotate the spindle and its attached head 50 while the same are being vibrated through the action of the crank shaft 24 and its connected helve next to be described.

The arm 8 is provided with a vertical hole 51 whose upper portion is somewhat larger than the lower part forming an annular shoulder therein upon which the flange of the

lower bearing is seated. The upper bearing is similar to the lower one except that its position on the spindle is reversed, the flanged end being disposed down, so that the flanged end of each bearing is adjacent the worm gear which runs therebetween, being slidably mounted upon the hammer spindle. The upper bearing and worm gear are held in place by means of a flanged cylindrical bushing 52 that is positioned in the larger upper end of the hole 51 and is provided with a screw 53 for securing the parts in place. From the foregoing it will be seen that the assembly of the parts is effected through the larger end of the hole 51.

The shaft 24 includes a crank portion 54 to which a bearing block 55 is attached for eccentric movement. A connecting rod 56 is threaded attached to this block and a lock nut 57 serves to anchor it in the block. This rod serves to operate the helve and is flexibly connected to the rear end portion through the following means: The helve which I will generally designate as 58 is made in part of a metal rocker member 59 and an attached member 60, the two being secured together forward of the pivot 61 by means of screw bolts 62 and a clamping plate 63. The metal member of the helve is provided with aligned oppositely disposed trunnions which form the pivots 61 upon which the helve rocks, said trunnions form the pivots that are journaled in bearings 69 of the before mentioned column. The rear end portion of the metal rocker member 60 of the helve is suitably forked to form spaced apart arms 64 to receive a block 65 and a pivotal member 66 mounted in said block. This pivotal member includes aligned reduced end portions 67 that are journaled in bushings 68 fitted in holes of the said arms 64 and have a free rocking movement in said bushings. This pivotal member 66 is provided with a vertically disposed hole 69 to accommodate the before mentioned rod 56 which extends therethrough and likewise through the rubber cushion members 70 that are mounted on said rod. These cushion members are located above and below the arm of the helve and are each secured upon the rod in a like manner as between plates 71 each of which are provided with a central hole to receive the rod and upon which said plates are mounted as against the opposite faces of the block 65. Washers 72 also mounted on said rod are positioned against the outer face of said cushion members 66 and are secured thereagainst by means of nuts 73—73 threadably mounted upon the rod.

It will thus be seen that a means of adjustment is provided, if required, as between the rear end portion of the helve and the bearing block 55 thus to provide a longer or shorter stroke for the helve.

The forward end portion of the wood

section 60 of the helve is provided with a hole 74 through which loosely extends a hammer rod 75, the lower end portion of which is secured to the reciprocator and rotatable hammer spindle 48 which carries the hammer head 50. Cushioning means is provided between this rod 75 and the helve member 60, comprising suitable rubber members 76 which are mounted upon the rod. A suitable washer 77 is positioned between each of the rubber members 76 and the helve 60 and a plate 78 is also positioned upon the rod and below the top rubber member and the end of spindle 48. Upon this rod above the top is positioned another washer 79 which is seated against the top side of the rubber 76. Nuts 80 which are threadedly attached to the upper threaded end of this rod 75 serve as an adjusting means for positioning the upper rubber and its washers with respect to the helve so as to insure and regulate the amount of play for the helve with respect to said bearing plate 78 and 79.

From the foregoing it will be understood that power for the machine is applied from the motor which serves to continuously drive the pulley 23. When it is desired to perform a riveting operation, the attendant places the work to be riveted upon the table and beneath the hammer and thereupon places his foot on the treadle in a way to engage the drive of the pulley with the crank shaft which in turn reciprocates the helve and vibrating hammer head, there being a relatively positive operating connection between the crank shaft and short end of the helve while the forward or longer end of the helve is provided with a slight lost motion, better to insure the desired operation of the hammer and longevity of the machine. Both ends of this lever are provided with suitable rubber cushions to properly co-operate with the helve and pitman connections in the one instance, and the helve and hammer connections in the other instance.

Having thus described my invention, what I desire to claim and secure by Letters Patent is:—

1. In a riveting machine, the combination of a pedestal including an arm having a shouldered hole therethrough smaller through one portion than the other, and a transverse hole intersecting the larger diameter, a cylindrical bearing within the smaller diameter and having an annular flange seated upon the shoulder in the first mentioned hole, a similar cylindrical bearing having an annular flange positioned in the larger diameter of the hole, a flanged cylindrical bushing surrounding the last mentioned bearing and seated against its flange, means for securing the flange of the larger bushing to the arm and the smaller bushings in position, a reciprocator and rotatable hammer spindle journaled in the bear-

ings, a worm gear positioned between the flanged ends of said bearings within the larger diameter of the hole and upon the hammer spindle to which it is splined for reciprocator movement of the spindle, means for reciprocating the hammer spindle in its bearings and gear, and means for rotating the worm gear and spindle.

2. A riveting machine, comprising a pedestal, a helve pivotally mounted therein including a metal rocker member having aligned trunnions and a rearwardly extended forked end portion, a reciprocatable hammer spindle carried by the forward end of the helve, means for rotating said spindle, a cylindrical rocker member having reduced end portions journaled in the forked end of helve and having a transverse hole through its central and larger portion, a block mounted on the rocker member and having a hole to register with the hole in the rocker member, a rod extended through said block and rocker member, washers situated on top and bottom sides of said block, rubber cushions carried on the rod and washers, a driving shaft, and adjustable eccentric connections between said shaft and helve.

Signed at Chicago in the county of Cook and State of Illinois this 16th day of September A. D. 1929.

JOHN G. McCLEAN.
